UNITED STATES PATENT OFFICE

PAUL FUHRMANN, OF PHILADELPHIA, PENNSYLVANIA

ATTACHMENT FOR VACUUM CLEANERS

Application filed August 2, 1927. Serial No. 210,058.

My invention relates to vacuum cleaners and more particularly to an attachment therefor.

After a room has been cleaned, there is usually a certain amount of dust in the air which may be caused to settle by using a fine spray of liquid and oftentimes it is desirable to deodorize a room after same has been cleaned by spraying the floor and furniture with a liquid solution.

An object of my invention is to provide an attachment for vacuum cleaners which may be operated in conjunction with the mechanism of such cleaners for spraying a room or the like with a liquid.

Another object of my invention is to so design the attachment that it may be readily attached to and removed from a standard vacuum cleaner.

The above objects are accomplished by providing a fluid tank with an outlet nozzle so arranged with relation to the fan casing of the vacuum cleaner that fluid pressure may be produced in said tank from said fan.

The mechanism may also be provided with means for diverting the fluid pressure into the dust bag of the vacuum cleaner, as may be desired.

In the drawings:—

Figure 1 is a perspective view of a vacuum cleaner on which an embodiment of my invention has been installed, and

Figure 2 is a detailed fragmentary view of the conduit connection and of the arrangement of valves therein, the same being shown partly broken away for this purpose, and

Figure 3 an enlarged detail view of a valve member.

In the accompanying drawings, I have shown my invention attached to one type of vacuum cleaner but it will be readily understood that structural changes may be made in the invention which will adapt it for use on any vacuum cleaner without departing from the spirit of the invention and that such changes may be easily within the ability of a mechanic skilled in the art.

Referring now more in detail to the draw-

ings, a tank 5 is shown mounted on the nozzle 6 of a vacuum cleaner with its back against the fan casing 7 and provided with depending lugs 8 which are preferably rigidly secured to the rear side of tank 5 and adapted to engage the rear side of nozzle 6 at either side of fan casing 7 so that, when the tank is seated on the nozzle, it is held against forward, rearward or lateral movement.

In adapting a vacuum cleaner to receive the attachment, it is usually necessary to make some alteration to the air outlet pipe, generally at a point close to the fan casing. In the present instance, the original conduit has been removed and a fitting 9 secured to fan casing 7 in any convenient manner. Fitting 9 is provided with two outlets 10 and 11; outlet 10 communicating with the dust bag 12, preferably through a conduit 13, while outlet 11 communicates with a bent pipe 14 which has its other end firmly secured to the top of tank 5. It will thus be seen that tank 5 is held against upward movement by pipe 14.

A valve member 15 is rigidly secured to a hinge pin 16 which is rotatably mounted in fitting 9 and adapted to be swung so as to cover either outlet 10 or outlet 11 by means of a handle 17 formed integral with hinge pin 16. A flanged gasket 18, preferably made of rubber, is disposed in outlets 10 and 11 and held therein by the flanges formed on conduit 13 and bent pipe 14. Each gasket 18 is provided with a tubular flange 19 which is of substantially the same size as the interiors of outlets 10 and 11 so that, when valve member 15 is swung in either a vertical or horizontal position, it will abut the edges of flange 19 and seal off one outlet while allowing free egress of air through the other outlet; the valve member being adapted to be held in this position by handle 17 engaging a spring clip 20, two of which are secured to the outside of fitting 8. Figure 1 shows how handle 17 is engaged by a clip 20 and Figure 2 shows how valve member 15 seals off outlet 11 and also shows, in dot-and-dash lines, how outlet 10 would be sealed if valve member 15 was swung into a

vertical position so that its handle engaged the other clip 20.

Conduit 13 and bent pipe 14 may be secured to fitting 9 in any desired manner but these parts have been shown as having flat 5 faced flanges between which gasket 18 may be placed. The adjacent flanges may be secured to one another by means of bolts or machine screws. When it is desired to remove tank 5 from the vacuum cleaner, the 10 bolts or screws joining pipe 14 to fitting 9 are removed; after which tank 5 may be lifted vertically from off nozzle 6.

Tank 5 is adapted to contain a liquid 21 which may be poured into the tank through 15 a filler pipe 22, preferably provided with a screw cap 23. A pipe 24 is rigidly secured to the top of tank 5 and extends downwardly so that its lower end is but slightly spaced from the bottom of the tank, as shown in 20 Figure 1. A fitting 25 is fixed to the top of tank 5 and adapted to have one end of a flexible hose 26 secured thereto; the hose being held on handle 27 by clips 28 when not 25 in use.

A nozzle 29, adapted to emit a very fine spray, is secured to the other end of hose 26 and may be of any desired type.

When it is desired to use the vacuum 30 cleaner, valve member 15 is swung upwardly to seal off outlet 11, as shown in Figures 1 and 2, thus allowing a free passage for the air from fan casing 7 to dust bag 12, as is customary. After the cleaning has been 35 done, or when it is desired to spray, dampen or deodorize a room, valve member 15 is swung into the position shown by dot-and-dash lines in Figure 2 so that air cannot enter conduit 13 but must pass out through outlet 40 conduit 11 and into tank 5 where it creates a pressure on the top of liquid 21 and forces same through pipe 24 and hose 26 to nozzle 29 and allows the liquid to be sprayed as desired. If 45 an atomizer nozzle were substituted for nozzle 29, the air pressure on liquid 21 would elevate same through one hose to the top of the liquid conduit while the hose connected to the air conduit would provide the necessary blast of air for operating the atomizer 50 nozzle.

While I have illustrated and described a certain embodiment of my invention, it will be understood that various modifications might be made without departing from the 55 spirit thereof, and that the device may be used for spraying, dampening, using disinfectants or insecticides, and that it may be readily adapted to other uses, and hence I do not limit myself to the precise construction set forth, but consider that I am at 60 liberty to make such changes and alterations as fairly come within the scope of the appended claims.

I claim:—

1. An attachment for vacuum cleaners in-

cluding a liquid tank, removably mountable upon a vacuum cleaner, a flexible conduit connected to the tank, a nozzle on the conduit, and means for supplying the tank with compressed air from the vacuum cleaner.

2. In a vacuum cleaner having an air passage therein, an attachment including a liquid tank mounted on the vacuum cleaner, a hose connected to the tank, a nozzle on the hose, a conduit connecting the tank to the air passage, and a valve for admitting air to and excluding air from the conduit.

3. In a vacuum cleaner having an air passage therein, an attachment including a liquid tank removably mounted on the vacuum cleaner, a hose connected to the tank, a nozzle on the hose, a rigid conduit connecting the tank to the air passage, a hinged valve for admitting air to and excluding air from the conduit, and means for holding the valve in open or closed position.

4. In a vacuum cleaner having a nozzle, a fan and a fan casing having an outlet pipe to which a dust bag is attached, an attachment including a liquid tank mounted on the nozzle, a hose connected to the tank and communicating with a pipe opening in the lower portion of the tank, a nozzle on the hose, a conduit communicating with the outlet pipe and the top of the tank, and a valve to control the current of air from the fan to the tank.

5. In a vacuum cleaner having a nozzle, a fan, and a fan casing having an outlet pipe to which a dust bag is attached, an attachment including a liquid tank mounted on the nozzle and abutting the fan casing, lugs on the tank engaging the back of the nozzle, said tank having a pipe therein, a hose connected to the pipe, said pipe opening in the lower portion of the tank, a nozzle on the hose, a rigid conduit removably connected to the outlet pipe and the top of the tank and communicating with the interior of each, and a valve to control the current of air from the fan to the tank.

In testimony whereof I have signed my name to this specification.

PAUL FUHRMANN.
